UNITED STATES PATENT OFFICE

103,947

DESIGN FOR AN ANTI-SLIP SHOE HEEL ATTACHMENT

Alfred Mancini, Roslindale, Mass.

Application June 4, 1936, Serial No. 63,009

Term of patent 14 years

To whom it may concern:

Be it known that I, Alfred Mancini, a citizen of the United States, residing at Roslindale, in the county of Suffolk and State of Massachusetts, have invented a certain new, original, and ornamental Design for Anti-Slip Shoe Heel Attachments, of which the following is a specification:

Reference is had to the accompanying drawing, forming a part of the specification, and in which:

Fig. 1 is a bottom plan view of an anti-slip shoe heel attachment showing my new design.

Fig. 2 is a top plan view of the attachment shown in Fig. 1.

Fig. 3 is a side elevation of the attachment as seen from any one of its four uniform upright sides.

I claim:

The ornamental design for an anti-slip shoe heel attachment, as shown.

ALFRED MANCINI.
